ILLUMINABLE NAME PLATE FOR AUTOMOBILES

Paul Freed, Los Angeles, Calif.

Application October 22, 1953, Serial No. 27,277

Term of patent 14 years

(Cl. D48—32)

To all whom it may concern:

Be it known that I, Paul Freed, have invented a new, original, and ornamental Design for Illuminable Name Plate for Automobiles, of which the following is a specification, reference being had to the accompanying drawing, forming a part hereof.

Figure 1 is a perspective view of an illuminable name plate for automobiles showing my new design.

Figure 2 is a side elevational view of the name plate.

Figure 3 is a plan view of the name plate.

Figure 4 is an end elevational view of the illuminated name plate looking toward the faces of the lights.

Figure 5 is an end elevational view of the name plate, looking toward the rear surfaces of the lights.

I claim:

The ornamental design for an illuminable name plate for automobiles, as shown.
